UNITED STATES PATENT OFFICE.

HERBERT W. SPELLMAN, OF NEW BRITAIN, CONNECTICUT.

PROCESS OF POLISHING METAL BODIES.

1,178,828.

Specification of Letters Patent. Patented Apr. 11, 1916.

Application filed May 21, 1915. Serial No. 29,538.

To all whom it may concern:

Be it known that I, HERBERT W. SPELLMAN, a citizen of the United States, residing at New Britain, Hartford county, State of Connecticut, have invented certain new and useful Improvements in Processes of Polishing Metal Bodies, of which the following is a full, clear, and exact description.

This invention relates to a new process of 10 polishing metal bodies, being particularly adapted for polishing the surface of cutlery and other steel bodies.

At the present time, and prior to my invention, in producing a highly finished surface upon metallic articles, and especially upon cutlery, crocus has been employed to produce what is known as a "crocus finish," the article being subjected to the action of a wheel treated with crocus. The preparation 20 of the wheel requires much skill and patience, and is at the best extremely slow, as is also the polishing operation, and the obtaining of a crocus finish upon articles is therefore very expensive.

The object of my invention is to produce a 25 process whereby little skill is required and the crocus finish may be imparted to articles in a comparatively inexpensive manner, such process being practised by the use of an apparatus illustrated in the drawings herein.

The following is a description of a process 30 embodying my invention and of an apparatus whereby the process may be carried out, the apparatus being illustrated in the accompanying drawings, of which—

Figure 1 shows a side elevation of the apparatus in its preferred form, part being broken away. Fig. 2 is an end elevation of the same with a portion shown in section. 40 Fig. 3 is a side elevation of the rotating spider with some of the arms removed. Fig. 4 is an end elevation of the same. Figs. 5, 6 and 7 are details of the arm supports, and Figs. 8 and 9 are side and plan views of the arms.

Referring more particularly to the drawings, 1 is a drum or casing having trunnions 2 extending from each side. This drum is formed in two parts, 3, 3', the latter of 50 which has a gear 4 cast thereon. The trunnions of the drum are mounted in journals 5 carried by supports 6. It is provided with a manhole and cover 7 secured thereto by thumb-nuts 8.

55 9 is a shaft mounted in suitable journals having a driving pulley 10 and a pinion 11

which engages the gear 4 for slowly driving the drum. Within the drum is a spider 12 mounted on the shaft 13, which is carried by journals 14 also supported by the 60 supports 6. These journals support the shaft 13 so that it is carried independently of the trunnions 2 of the spider and are separated from the bearings 5 so as to leave spaces between them. In these spaces are 65 rings 15 secured to the shaft 13 by set screws 15' so as to center the spider within the drum. The result of thus supporting the drum and spider by independent means is that the two moving parts 1 and 13 do 70 not grind upon each other, and any polishing material which works out from the drum through the trunnions does not materially cut or abrade either the exterior of the shaft or the interior surface of the trunnion. On 75 the shaft 13 is a pulley 16 which is driven by a belt 17 from the pulley 18 on the counter-shaft 19. From a second pulley 20 on the shaft 19 a belt 20' also passes to the pulley 10 on the gear-shaft 9. The parts 80 are so arranged that when the counter-shaft 19 is slowly driven the spider and drum are also slowly driven and in opposite directions. The drum is preferably made about 85 forty inches in internal diameter. The spider 12 is provided with lateral projections 21 and pivotally supported on them are carriers 22, 22', each of which is provided with an adjusting arm 23 and a set screw 24 so that the carriers can from time 90 to time be adjusted in different positions. Each carrier is provided with three sockets 25 having set screws 26 for holding arms 27. The arms are also provided with sockets 28 having set screws 29 for holding the shanks 95 of the knives or other articles to be polished. The sockets are so disposed that those on successive carriers are out of line with each other. The major axes of the knives lie in 100 their planes of revolution and are substantially at right angles to the arms. The drum 1 is about one-quarter filled with pulverulent polishing compound 30.

In carrying out my process in its preferred form this compound is composed of 105 crocus, a hard abrading substance such as finely divided carborundum or emery and, in some instances, cork crumbs, such as the granulated cork used for packing grapes. The cork is useful when the compound is at 110 all moist since it keeps it from packing. The hard abrading substance acts as an en-

livener for the crocus and produces more rapid polishing action without materially preventing the desired high polish. I preferably use a little more carborundum or 5 emery, by weight, than crocus.

In carrying out my process the articles to be polished are secured to the arms 27 on the spider and the spider and drum are then slowly rotated in opposite directions. This 10 gives the steel the desired finish when the process is otherwise properly carried out. In order to prevent grooving or scoring of the surface being polished I change the angular positions of the axes of the 15 articles relative to their paths through the compound from time to time by adjusting the carriers 22, 22'. Thus I preferably change the positions once every twenty-four hours. A complete polishing may require 20 four or five days of twenty-four hours each and in some instances six or seven such days, depending on the original condition of the surfaces. A period of forty-eight hours may be permitted to elapse before the first 25 change in position. The rotation of the drum keeps the ingredients of the compound thoroughly mixed and prevents it from packing, it being continually turned over as the apparatus operates. With flat articles 30 such as knives the relative motion is always in the same direction, point first, and the faces are kept in planes at right angles to the axis of revolution. With forks the direction of rotation is reversed from time to 35 time so as to polish the rear surfaces.

When the process is carried out as above described the metal surface takes on a remarkable mirror-like polish, such as has heretofore been attained only by hand polishing. 40 The apparatus shown and described is shown and described in a companion application to be filed by me on the same day herewith.

As will be evident to those skilled in the 45 art, my invention permits of various modifications without departing from the spirit thereof or the scope of the appended claims.

What I claim is:

1. The process of polishing an article 50 which consists in surrounding it with a mass of pulverulent polishing material, producing relative movement between said article and said material so that said article slowly moves relatively along a definite path through said material, and from time to time changing the angle between the axis of said article and the axis of the path formed thereby through said material.

2. The process of polishing an article 55 which consists in surrounding it with a mass of pulverulent polishing material comprising crocus and an enlivening material, producing relative movement between said arti-

cle and said material so that said article slowly moves relatively along a definite path 65 through said material, and from time to time changing the angle between the axis of said article and the axis of the path formed thereby through said material.

3. The process of polishing a flat article 70 which consists in surrounding it with a mass of pulverulent polishing material, producing relative movement of rotation between said article and said material so that said article slowly moves relatively along a definite path through said material, and from time to time changing the angle between the axis of said article and the axis of the path formed thereby through said material, the 75 faces of said article being kept at right angles to its axis of revolution.

4. The process of polishing a flat article, which consists in rotating it about an axis while surrounded by polishing material, holding it meanwhile so that its major axis describes a plane parallel to the sides of said article and is at an angle to a radius of the circle described by such rotation, and from time to time changing the angular position 85 of said major axis within said plane. 90

5. The process of polishing an article which consists in surrounding it with a mass of pulverulent polishing material, producing relative movement between said article and said material so that said article slowly 95 moves relatively along a definite path through said material, and from time to time changing the angle between the axis of said article and the axis of the path formed thereby through said material, the 100 changes in position being at the ends of periods covering several hours.

6. The process of polishing an article which consists in surrounding it with a mass of pulverulent polishing material, producing relative movement between said article and said material so that said article slowly moves relatively along a definite path through said material, and from time to time changing the angle between the axis of 105 said article and the axis of the path formed thereby through said material, and turning over the polishing material during the polishing period.

7. The process of polishing an elongated 115 article, which consists in rotating it about an axis while surrounded by polishing material and from time to time changing the position of its axis relative to the axis of the path described by it, said article being supported by its rear end with its axis kept 120 pointing in the direction of its movement.
